United States Patent Office.

JOHN JOHNSON, OF SACO, MAINE.

Letters Patent No. 60,899, dated January 1, 1867

IMPROVED MODE OF GATHERING AND TREATING AURIFEROUS SANDS FROM THE BEDS OF RIVERS.

The Schedule referred to in these Letters Patent and making part of the same.

TO ALL WHOM IT MAY CONCERN:

Be it known that I, JOHN JOHNSON, of Saco, county of York, State of Maine, have invented a new and improved System of Removing and Treating Auriferous Sands, Gravels, &c., from the Beds of Rivers; and I do hereby declare that the following is a full and exact description thereof.

The nature of my invention consists in the application of suitable motive power, centrifugal pumps, pipes, or tubes, concentrating apparatus, &c., and amalgamator placed on a suitable barge for the purpose of removing from the bed of rivers the auriferous sands, &c., and treating the same for the recovery of the free precious metals.

To enable others to make and use my invention, I will proceed to describe its construction and operation. (See my Patent, No. 56,948, improved dredging machine, dated August 7th, 1866.)

The principal feature of my invention consists in providing a boat or barge, (having the requisite boat appliances,) of suitable size to carry upon its deck a steam boiler, engine, pump, tank, tube, or trunk, &c. The boat I make rectangular, about six times as long as wide, and in depth, say two feet, so as to draw when ready for work as little depth of water as is practicable. On the deck of this flat-boat I place the motive power for actuating the pump, &c., and on the deck I also place a strong wrought-iron case or box, air and water-tight, except through the tube and pump. To this vessel or case I attach a suitable tube or trunk, six or more inches in diameter, of the required length, and somewhat pliable, in such a manner that the outer end of this tube or trunk, of proper shape, may be lowered upon the bed of the river to be ready to remove the auriferous sands, &c., and the inboard end properly secured to the iron box. Upon this wrought-iron case or tank, I set my pump, the foot valve of which I adjust to within a few inches of the bottom, more or less. Within this case I secure a suitably strong wrought-iron grating, and so adjust it that when rocks, pebbles, &c., are brought up with the gravels and sands they may be screened from the latter so as not to pass through the pump. Almost directly opposite to the tube, and in a line with the tube or trunk, I have an air-tight door that can be opened at pleasure for the purpose of removing the accumulated rocks, &c., whenever requiring to do so. Within this wrought-iron case or tank, and near the bottom, I place a false bottom made up of iron and wire gauze, or any other suitable substance. Between the bottom and the false bottom, I introduce water under suitable head or pressure for the purpose of preventing the consolidating or settling of the sands as they enter from without through the tube or trunk previous to their entering the pump. This false bottom I place at an angle, so that as the sands come in through the tube and grating they fall with the water upon the false bottom. A volume of water being caused to pass from beneath upwards, and the false bottom being set at an angle and agitated, causes a constant flowing outward of the semi-fluid auriferous sands, at the same time concentrating, or settling the richer and heavier particles of fine gold near to, beneath, but out of the direct influence of the action of the pump, thereby retaining the richer gatherings within this air-tight case, and these rich accumulations accessible only to the managing agent by lock and key. As the sands are drawn up from the bottom or bed of the river, through the tube and separating receptacle, it is found that some of the finer particles of gold escape with the sands and water, and as the sands and water containing some of this fine gold flow out through the pump from this receptacle; to secure them, I place contiguous to the pump suitable amalgamating apparatus, there to receive and well distribute the auriferous sands that the particles escaping from the receptacle be there taken up by the amalgamator before passing these sands overboard beneath the water again. When not employing the power for pumping or dredging, I so arrange it, that at pleasure, with suitable propeller and belting, I propel the boat to any suitable locality. I also have on board all the needful appliances for anchoring, warping, and otherwise making efficient this apparatus for the purpose intended. It will be clearly seen that an efficient steam engine, say one of fifteen horse power, actuating a centrifugal pump, properly located on the air-tight chamber, and from this chamber a tube or trunk of suitable length and size to dredge in the required depth of water, and also concentrating and amalgamating with separating; the whole on a barge and operated, constitutes a gold-obtaining system new and useful, and more than equaling in efficiency the labor of a thousand men with the spade or boat shovel. On board of the barge, in some localities, I can dispense with the concentrating and separating air-tight box; connecting the tube or trunk directly with the pump, and at the outflow place suitable separating and washing apparatus.

What I claim, and desire to secure by Letters Patent, is—

The process of raising and treating auriferous sands found at the bottom of rivers and lakes substantially as described.

I claim the combination of the pumping apparatus with separators, concentrators, agitators, and amalgamators when they are operated on board a floating barge substantially as described.

Witnesses:

FRANK C. JOHNSON,
MOSES EMERY

JOHN JOHNSON.
